Primary Examiner — Susan Bennett Hattan*Assistant Examiner* — Jennifer Wright(74) *Attorney, Agent, or Firm* — Avvno Law P.C.(57) **CLAIM**

I claim the ornamental design for night goggles, as shown and described.

DESCRIPTION

FIG. 1 is a front perspective view of night goggles.

FIG. 2 is a rear perspective view of the night goggles of FIG. 1

FIG. 3 is a top view of the night goggles of FIG. 1.

FIG. 4 is a front view of the night goggles of FIG. 1.

FIG. 5 is a bottom view of the night goggles of FIG. 1.

FIG. 6 is a rear view of the night goggles of FIG. 1.

FIG. 7 is a side view of the left side of the night goggles of FIG. 1; and,

FIG. 8 is a side view of the right side of the night goggles of FIG. 1.

The broken lines depict parts of the night goggles and form no part of the claimed design.
